FOREIGN PATENT DOCUMENTS

EM 004542744-0001 * 12/2017

Primary Examiner — Paula Allen Greene

(57) **CLAIM**

The ornamental design for earphones, as shown and described.

DESCRIPTION

FIG. 1 is a right side view of the earphones.

FIG. 2 is a rear view of the earphones.

FIG. 3 is a top view of the earphones.

FIG. 4 is a bottom view of the earphones.

FIG. 5 is a left side view of the earphones.

FIG. 6 a front view of the earphones.

FIG. 7 is a rear left top perspective view of the earphones; and,

FIG. 8 is a front right top perspective view of the earphones. The broken lines depict environment that forms no part of the claimed design.

1 Claim, 3 Drawing Sheets---
